AIR OR GAS COMPRESSOR

Raoul Vendôme, Paris, France, assignor to Marcel
Franck, Paris, FranceApplication August 21, 1935, Serial No. 37,150
In France September 26, 1934

1 Claim. (Cl. 230—190)

This invention relates to improvements in air or gas compressors and more especially in air compressors designed to be applied to spraying apparatus for atomizing liquids.

5 It concerns particularly compressors of the kind in which a piston is driven by means of pressure acting upon it in the body of a pump and returned to its first position when set free, through the action of a spring; it is more especially characterized in that the return stroke of the piston is limited by abutment means placed inside the pump body. When once the piston has been set in position it is not necessary to fix a stop ring or the like upon the open end of the pump body 10 or cylinder, the assembling and the taking to pieces of the piston are thus simplified and the outer shape of the apparatus is remarkably neat and smooth.

According to one mode of execution of the invention, the piston is mounted upon the outer end of a piston rod made in one or several parts 20 slideable in each other, the part farthest from the piston being secured at its end to the bottom of the cylinder. When the piston rod is fully extended in the manner of a telescope the piston is exactly level with the cylinder edge.

The piston rod is preferably hollow and opened to the outside and it passes through a hole provided in the piston, its inner end communicating 30 through a suitable orifice with the interior of the cylinder. The pressure air or gas flows out through an orifice provided near the bottom of the cylinder.

In order that the invention may be fully appreciated the same will now be described with reference to the accompanying drawing which illustrates by way of example one practical form of execution of my invention.

Fig. 1 is an axial sectional view drawn on a 40 larger scale along the line I—I of Fig. 2 of a compressor constructed according to the present invention.

Fig. 2 is an elevation, drawn on a smaller scale of a spraying apparatus provided with a compressor of the present system.

Fig. 3 is a similar view illustrating another way of fixing the compressor to the spraying apparatus.

The compressor is shown as comprising a cylinder 1 in which a circular shaped piston 2 is slidably mounted. Said piston is centrally bored and mounted upon a small sleeve 4. It is provided with a disk 7 of leather or other flexible material which is secured by means of a washer 8, the 55 whole being clamped against the inner face of

the piston 2 by means of a nut 9 which takes upon an outer screwthread provided on the outer surface of the sleeve 4. The latter constitutes the first member of an extensible rod composed of the hollow members 4, 5, 6 which may slide in each other and whose extension is limited by flanges 4a, 5a, 5b, 6a which abut against one another when the members 4, 5, 6 are fully extended, the outer surface of the piston coming in that position exactly on a level with the edge of the 10 cylinder 1. The end of the hollow member 6 farthest away from the piston is fixed, preferably by screwing in the bottom 1' of cylinder 1, and is provided with a small orifice 10 which puts the interior of the hollow members 4, 5, 6 in communication with the cylinder chamber 1. A spring 11 tends to force the piston 1 towards the exterior. The cylinder is provided with a delivery opening 12 preferably located laterally near the bottom 1' of the cylinder which is connected 15 for example with a spraying nozzle 13.

The mode of operation of the above described compressor is as follows:

The piston 2 is pushed into the cylinder 1 by obturating with the finger the opening 14 of the 25 member 4. The members 4, 5 and 6 slide one upon the other and the air in the cylinder 1 is driven through the opening 12 towards the place where it is to be used in the direction of the spraying nozzle 13 for example. On the piston being then 30 set free it is returned by the spring 11 in its outer position in which it is retained through the abutment of the flanges 4a, 5a, 5b, 6a of the members 4, 5, 6 against each other. During this return stroke, the orifice 14 being uncovered, the 35 outer air fills the cylinder as it flows inside the members 4, 5, 6 and through the orifice 10.

Fig. 2 shows the compressor mounted upon the head of a spraying apparatus, the cylinder being preferably welded directly upon said spraying 40 apparatus.

The compressor may also be connected to the spraying apparatus in any other suitable manner, by means of a metal tube 16 for example, as shown in Fig. 3.

It is to be understood that the construction disclosed herein is one of the preferred forms of my invention but that the invention may also be applied to air or gas compressors devised for other uses.

What I claim and desire to secure by Letters Patent of the United States is:

An air compressor more especially designed for spraying apparatus which comprises in combination a hollow cylindrical body having a bottom 55

closing one end thereof, a delivery opening being formed in said body adjacent said bottom to connect said body with a spraying apparatus, a piston movable in said body, a spring situated inside said body and actuating said piston towards the open end of the body, a hollow rod secured at one end to the bottom of the body and constituted by telescoping members, the piston being secured to the other end of said rod, said rod being open

to the outside atmosphere and communicating with the interior of the body through an orifice formed in the rod adjacent its first-mentioned end, and abutments upon the hollow telescoping rod members for the purpose of limiting the piston stroke so that the latter comes to a level with the edge of the body when the hollow rod is fully extended. 5

RAOUL VENDÔME.
